(57) CLAIM

The ornamental design for pants, as shown and described.

DESCRIPTION

FIG. 1 is a perspective view of pants showing my new design;

FIG. 2 is a front view in elevation thereof;

FIG. 3 is a rear view in elevation thereof;

FIG. 4 is a left side view thereof; and

FIG. 5 is a right side view thereof.

FIG. 6 is a perspective view of pants showing my new design;

FIG. 7 is a front view thereof;

FIG. 8 is a rear view thereof;

FIG. 9 is a left side view thereof; and,

FIG. 10 is a right side view thereof.

The broken line illustration in the drawings depicts portions of the pants that form no part of the claim. The stippling in the drawings indicates seam placement. The broken, dot-dash line in the drawings indicates a boundary line and, as such, is not part of the claimed design.
